UNITED STATES PATENT OFFICE.

G. VAN NESS COVERT, OF FARMER VILLAGE, ASSIGNOR OF ONE-HALF TO
DANIEL L. HAMILL, OF TROY, NEW YORK.

FIRE-ESCAPE.

SPECIFICATION forming part of Letters Patent No. 309,527, dated December 23, 1884.

Application filed May 6, 1884. (No model.)

To all whom it may concern:

Be it known that I, G. VAN NESS COVERT, of Farmer Village, Seneca county, State of New York, have invented a new and useful 5 Improvement in Fire-Escapes, of which the following is a specification.

My invention relates to that class of fire-escapes which are portable and that form no part of the building in which they are used, they 10 being made to be hung up in a room or to be carried by travelers in a trunk.

My invention consists, as will be more fully detailed hereinafter in connection with its 15 illustration, in the combination of a roller having a spool form that is adapted to have a rope wound thereon, one end of said rope being attached to the roller and the other end provided with a hook to connect the device, a recess or groove in revolution on said roller at each end 20 outside of that part in which the rope is wound, friction-straps in said recesses or grooves, a body-strap provided with arm-straps, and which body-strap at each end is attached to one of said friction-straps, and holder-straps 25 on each end of the roller outside of the friction-straps, said holder-straps being provided with handles for the suspended person to take hold of to raise the weight of the body from off the friction-straps, so that a descent may be 30 made by the unwinding of the rope from off the roller.

Accompanying this specification, to form a part of it, there are two plates of drawings, containing three figures illustrating my invention, with the same designation of its parts by 35 letter reference used in all of them.

Of these illustrations, Figure 1 shows a perspective of the apparatus containing my invention. Fig. 2 shows a longitudinal vertical 40 section taken on the line $x' x'$ of Fig. 1. Fig. 3 shows a cross vertical section taken on the line $x^2 x^2$ of Fig. 1, said illustration being taken through one of the recesses or grooves and the friction-belt which engages therewith.

45 The several parts of the device are designated by letter reference and their function described as follows:

The letter R designates a roller, made of wood or other equally light material, and constructed 50 with the flanges F F, arranged at each end

of the spool-form receptacle B, and adapted to have wound thereon a rope, C, one end of which is attached to the roller at a, and the other end is provided with a hook, H, for attachment to the inside of the window-sill of a 55 room or any other suitable place of connection.

The letter S indicates a groove or recess made to encircle the roller at each end outside of the spool-flanges F, and the letters D indicate a friction-strap arranged in each of the said 60 recesses or grooves. The circumference of the said grooves or recesses is made to be enough greater than the circumference of the spool part of the roller to have the friction of the straps D and to resist the revolution of the 65 roller and the unwinding of the rope from off the spool part of the roller when a weight is suspended from the friction-straps.

The letter E indicates a body-strap, each end of which is attached to one of the friction-straps D by hooks, and this body-strap is provided with arm-straps A, through which the 70 arms of the person making a descent by means of the device are passed.

The letters N indicate holder-straps arranged 75 in the extreme end of the roller, and made to encircle the latter each within an encircling groove, g. These holder-straps are each made with a handle, h, and by means of which holder-straps and handles the person suspended by 80 the body and arm straps may raise the weight of the body from off the friction-straps, so as to permit a descent to be made.

The device thus illustrated and described is used in the following manner: The hook H 85 being connected with a window-sill or a bedstead within the room from which a descent is to be made, by passing the arms through the straps A A so that the strap E is across the back of the person desiring to make the descent, the body may be swung from out the window, and, its weight coming upon the friction-straps D, will not descend, but remain suspended. To make the descent, the person 90 must grasp the holder-straps by means of the handles h and raise the weight of the body from off the friction-straps D and their engagement with the surfaces of the recesses S, when the roller will turn and the rope unwind, allowing the body to descend. When it is de- 95 100

sired to arrest the descent by releasing the hold upon the holder-straps, the weight of the body is again thrown onto the friction-straps, and this stops the rotation of the roller and the unwinding of the rope. Thus the descent of a person by means of the device can be regulated without taking hold of the rope.

While I have shown a body-strap made with arm-straps, I do not limit my invention to the use of one so made, as the other factors would perform the same office whether the form of strap shown was used or any form of strap by which the weight of the body was suspended from the friction-straps was employed.

15 The friction-straps D, I prefer to make of leather, each of them having a broad bearing-surface within the recesses in which they are placed, with the diameter of the roller thereat greater than that part of the roller on which 20 the rope is wound at the spool part.

The holders N and their handles may be made of either metal or leather.

Having thus described my invention, what I claim, and desire to secure by Letters Patent, 25 is—

1. In a fire-escape, the combination of the roller R, made with the spool part B, an encircling-recess, S, at each end of the spool part, with the diameter of the roller greater thereat 30 than at the spool part, with the encircling

groove g at each end of the roller, the friction-straps D within said recesses S, the holder-straps N, made with handles h, said holder-straps arranged within the grooves g, the body-strap E at each of its ends attached to one of the friction-straps, and the rope C, one end attached to the roller, and at the other end provided with the hook H, said parts being arranged to operate substantially in the manner herein shown and described. 35

2. In a fire-escape, the combination of the encircling recesses S, made in the roller R, the friction-straps D, arranged in said recesses, the encircling groove g, made in said roller near its ends, the holders N, arranged in said grooves 45 g, the body-strap E, at each end attached to one of the friction-straps, the spool part B, made in the said roller, the rope C, attached at one end to said roller, and at the other end provided with the hook H, the said parts being 50 constructed and arranged to operate substantially as and for the purposes set forth.

Signed at Farmer Village, April 24, 1884, in the presence of the two witnesses whose names are hereto written.

G. VAN NESS COVERT.
